Des. 229,342
Patented Nov. 20, 1973

229,342

WEATHER VANE

Jack Fickler, 2705 S. 106th St., Omaha, Nebr. 68124

Filed Nov. 26, 1971, Ser. No. 202,723

Term of patent 14 years

Int. Cl. D10—06

U.S. Cl. D52—6 D

FIG. 1

FIG. 2

FIG. 3

FIG. 4

FIG. 1 is a bottom and side perspective view of a weather vane showing my new design;

FIG. 2 is a front elevational view thereof;

FIG. 3 is a top plan view thereof;

FIG. 4 is a side elevational view thereof, the opposite side being a mirror image thereto.

I claim:

The ornamental design for a weather vane, substantially as shown and described.
